UNITED STATES PATENT OFFICE.

WILLIAM H. RANKIN, OF WALTHAM, MASSACHUSETTS.

FILLING-FEELER MECHANISM.

1,187,094.

Specification of Letters Patent. Patented June 13, 1916.

Application filed September 2, 1915. Serial No. 48,5

To all whom it may concern:

Be it known that I, WILLIAM H. RANKIN, a citizen of the United States, residing at Waltham, in the county of Middlesex and State of Massachusetts, have invented certain new and useful Improvements in Filling-Feeler Mechanisms; and I do hereby declare the following to be a full, clear, and exact description of the invention, such as will enable others skilled in the art to which it appertains to make and use the same.

The present invention relates to an improvement in filling-feeler mechanisms for looms and more particularly, to an improvement in such mechanisms for weft replenishing looms.

In weaving high grade fabrics, it is desirable that no short wefts should be woven into the cloth. Accordingly, looms have been provided with mechanisms for determining the amount of filling on the bobbin in the active shuttle; and when the filling has been exhausted to a predetermined extent, that is, when there is only enough filling left on the bobbin to suffice for two or three picks across the lay, devices are brought into operation to effect either the stoppage of the loom or filling replenishment. These mechanisms for determining the amount of filling in the active shuttle, and the connections between them and the devices for causing loom stoppage or filling replenishment, have hitherto been more or less complicated, with the result that owing to the excessive jars to which they and the devices controlled by them are subject incident to the operation of the loom, such mechanisms have often failed to detect critical exhaustion of the filling, that is to say, exhaustion of the filling to a predetermined extent. Consequently, the filling on the bobbin has been often entirely exhausted and a short weft woven into the cloth, thereby impairing its quality.

One object of the present invention, therefore, is the production of a filling-feeler mechanism which will operate with certainty to effect loom stoppage or filling replenishment when the filling on the bobbin has been exhausted to an extent beyond which it is unsafe to go because of the

liability of weaving a short weft thread into the fabric.

A further object of the invention is to simplify the construction and arrangement of the connections between the filling-feeler mechanism and the devices controlled thereby.

Another object of the invention is the production of a filling-feeler mechanism (if it is applied to a loom of the weft-replenishing type), having provision whereby the filling-feeler may be utilized to prevent the operation of the weft-replenishing mechanism in case the shuttle is improperly boxed.

A still further object of the invention is to produce a filling-feeler mechanism in which the filling-feeler is constructed and arranged to be withdrawn out of the shuttle, after the determination of the amount of filling in the active shuttle and before the lay reaches its forward center.

Further objects of the invention consist in certain novel constructions and arrangements of parts, the advantages of which will be apparent to those skilled in the art.

To the accomplishment of these various objects, the present invention contemplates a filling-feeler mechanism mounted upon the same end of the loom with the filling-replenishing mechanism and having provision, upon predetermined exhaustion of filling in the active shuttle, for positioning the parts of the weft-replenishing mechanism so that filling-replenishment may be effected upon the same forward beat of the lay upon which the filling-feeler mechanism is indicated. The means by which the filling-feeler mechanism operatively positions the transerrer devices of the weft-replenishing mechanism comprises an actuator adapted to be brought into engagement with the transerrer devices so that, when critical exhaustion of filling is indicated, the devices will be positioned in the path of a bunter on the lay and the operation of the weft-replenishing mechanism effectuated.

While the improved filling-feeler mechanism of the invention is illustrated and described as applied to a weft-replenishing loom, it will be understood that the appli-

cation of the invention is not limited to weft replenishing looms but may be used in connection with other types of looms.

The various features of the present invention are described in the following specification and particularly pointed out in the appended claims.

In the accompanying drawings illustrating the preferred form of the invention, Figure 1 is a side elevation of a loom showing the application of the improved filling feeler mechanism thereto; Fig. 2 is a partial side elevation on an enlarged scale, illustrating the positions of parts of the weft replenishing mechanism and co-operating parts of the filling feeler mechanism just previous to filling replenishment; and Fig. 3 is a plan of the parts shown in Fig. 2 with portions of the transerrer hammer 20 and shuttle magazine removed.

The loom to which the improved filling feeler mechanism is applied may be of any usual or preferred construction, that shown in the illustrated embodiment of the invention being an ordinary four-color loom. The lay 5 is mounted upon a lay sword 6 pivoted at 7 to the loom frame 8. An oscillatory movement is imparted to the lay from the crank shaft 9 by a pitman 10. On the right-hand end of the lay is located a fixed shuttle box 11, and on the left-hand end of the lay are located the vertically shifting shuttle boxes 13. A horizontally reciprocating filling magazine 14 is mounted on the right-hand end of the loom over the path of movement of the fixed shuttle box 11. The filling magazine 14 slides upon a magazine support 15 secured to the loom frame. A lip 16 projecting laterally from the magazine support 15 prevents the heads of the filled bobbins 17 from displacement, except when they are positioned over the shuttle when it is boxed at the right-hand end of the lay. To permit the insertion of a filled bobbin into the active shuttle, the lip 16 is cut away at that place which is directly over the right-hand shuttle box when the lay is on its forward center. The filling magazine 14 has as many compartments as there are shifting boxes and each compartment contains a supply of filling of the same color and character as the filling in the corresponding shifting shuttle box. The shifting shuttle boxes are reciprocated vertically in order to present a shuttle containing filling of the proper color to the picker, and the filling magazine is reciprocated horizontally in timed relation with the reciprocations of the shifting shuttle boxes. The reciprocatory movement is imparted to the shifting shuttle boxes by an arm 18 controlled by the pattern mechanism. The connections between the shifting shuttle boxes 13 and the arm 18 consist of a vertically reciprocating rod 19 and

a link 20 pivoted at its lower end to the rod 19 and at its upper end to the arm 18. The filling magazine 14 is constructed to move in unison with the shifting shuttle boxes 13 so that, when the lay is on its forward center, a bobbin containing filling of the same color and character as the filling in the active shuttle will be positioned over the fixed shuttle box 11. The reciprocatory movements of the filling magazine 14 are imparted to it by the arm 18. The connections between the magazine 14 and the arm 18 consist of a bell crank lever 22 pivoted to the loom frame, and a link 23 the upper end of which is articulated with the lower arm 24 of the bell crank lever 22 by means of a pin and slot connection in order to regulate the extent of movement of the magazine 14. The lower end of the link 23 is pivoted to the arm 18. The parts above 85 enumerated, their actuating mechanism and their mode of operation, together with other parts of the loom necessary to a disclosure of the present invention, are well-known and understood by those skilled in the art 90 without further explanation.

The improved filling feeler mechanism operates when the filling in the active shuttle has been exhausted to a predetermined extent, to bring the parts of the weft replenishing mechanism into position to effect weft replenishment, by the time the lay reaches its forward center, on the same beat upon which the filling feeler operation takes place. To permit the filling feeler operation and the weft replenishing operation to take place on the same forward beat of the lay, the filling feeler mechanism is situated on the same side of the loom as the weft replenishing mechanism. 105 The improved filling feeler mechanism comprises a filling feeler 25 having a filling engaging tip 26 which is adapted to be projected through the usual apertures cut in the front walls of the fixed shuttle box 11 and of the shuttle 27 respectively. The forward end or shank of the filling feeler 25 is received in a housing 28 mounted upon a bracket 21 secured to the right-hand end of the breast beam 29. The filling feeler 25 is yieldingly pressed toward the lay and is normally in position to be engaged by the filling in the active shuttle when the shuttle is boxed at the right-hand end of the lay. Pivoted on the rearward end of the filling feeler 25 just forward of the filling engaging tip 26, is a feeler controller 30 having a shuttle engaging tip 31 and a transerrer latch actuator 32 extending forwardly toward the breast beam. The shuttle engaging tip 31 is threaded on its forward end and is received in a threaded hole in an upwardly extending portion 33 of the controller, so that it may be adjusted relatively to the filling engaging tip 26. A checknut 190

34 secures the shuttle engaging tip 31 in adjusted position. When a substantial amount of filling remains on the bobbin in the active shuttle, the filling engaging tip 31 does not strike the front wall of the shuttle; but when the filling has been exhausted to a predetermined extent, the shuttle engaging tip 31 is contacted by the front wall of the shuttle so that the feeler controller 30 is oscillated on its pivot and the forward end of the transerrer latch actuator 32 is depressed until it rests on the upper surface of the filling feeler housing 28, upon which it slides to the point of engagement with a part of the weft replenishing mechanism; whereupon, the weft replenishing mechanism is actuated to effect the transfer of a fresh supply of filling in the active shuttle.

20 The filling feeler 25 is normally in position to be engaged by the filling in the active shuttle when the shuttle is boxed on the right-hand end of the lay, and after the determination of the amount of filling in the active shuttle by the filling engaging tip, the filling feeler 25 is retracted from before the forwardly beating lay in order that the filling engaging tip 26 may not interfere with the insertion of a fresh supply of filling in the shuttle. The means for retracting the filling feeler 25 from before the lay comprises a filling feeler controlling cam 36 secured to the cam shaft 37. The connections between the filling feeler 25 and the filling feeler controlling cam 36 consist of a lever 38 pivoted at 39 to the loom frame, and a bell crank lever 40 pivoted at 41 to the frame of the loom. The upper end of the vertically disposed arm 42 of the bell crank lever 40 is articulated with the forward end of the shank of the filling feeler 25 by a pin and slot connection 43; and the horizontally disposed arm 44 of the bell crank lever 40 is articulated with the free end of the lever 38 by a pin and slot connection in order that the amount of movement imparted to the filling feeler 25 by the filling feeler controlling cam 36 may be regulated. The free end of the horizontally disposed arm 44 of the bell crank lever 40 is provided with a vertically disposed slot 45, and the free end of the lever 38 is provided with a longitudinally disposed slot 46. The arm 44 and the lever 38 are connected by a bolt 47 which passes through the slots 45 and 46. The position of the bolt 47 in the slot 45 determines the amount of throw of the filling feeler 25. When the amount of throw of the filling feeler 25 is determined, the bolt is secured to the arm 44 in adjusted position in the slot 45. The construction of the slotted end of the lever 38 and its connection with the arm 44 through the pin 47, is such that when the lever 38 is actuated by the cam 36, there is a movement of the slot 46 on the pin 47. As

shown in Fig. 1, the filling feeler 25 is at the limit of its rearward movement toward the lay in position to determine the amount of filling on the bobbin in the active shuttle on the next forward beat of the lay. When the filling feeler 25 is in this position, a roll 49 carried by the lever 38 is out of engagement with the cam 36. Immediately after the engagement of the filling with the filling engaging tip 26,—when there is a substantial amount of filling on the bobbin,—and the engagement of the front wall of the shuttle with the shuttle engaging tip 31,—when the filling has been exhausted to a predetermined extent,—the active part 50 of the cam 36 contacts with the roll 49, thereby lifting the forward end of the lever 38. The upward movement of the free end of the lever 38 oscillates the bell crank lever 40 on its pivot 41 and swings the vertically disposed arm 42 of the lever 40 to the left. The movement of the arm 42 to the left draws the filling feeler 25 forward out of the path of the lay, and if critical exhaustion of filling is indicated, thereby permits filling replenishment to take place at the requisite time. It will be observed that the distances between the working ends of the lever 38 and of the bell crank lever 40 to their fulcrums and to their points of application respectively, are such that a very slight movement upward of the roll 49 carried by the lever 38 suffices to impart a considerable longitudinal movement relatively to the filling feeler 25, so that the retreat of the filling feeler before the lay is extremely rapid.

When critical exhaustion of filling in the active shuttle has been indicated and the front wall of the shuttle contacts with the shuttle engaging tip 31,—thereby oscillating the feeler controller 30 on its pivot until the forward end of the transerrer latch actuator 32 rests on the upper surface of the filling feeler housing 28,—the forward movement of the end of the transerrer latch actuator brings it into engagement with an abutment 52 projecting upwardly from a transerrer latch 53 pivoted at 54 to the lower extremity of a downwardly extending arm 55 of the transerrer hammer 56. The transerrer hammer 56 is pivoted at 57 on a bracket 58 secured to the breast beam 29. A spring 59 encircles the pivot pin 57 and tends to maintain the transerrer hammer 56 in raised position. The continued forward movement of the transerrer latch actuator 32 after its engagement with the abutment 52, causes the transerrer latch 53 to swing on its pivot 54 until the rearward end of the latch 53 is brought into the path of movement of a bunter 61 secured to the front of the lay 5. The engagement of the transerrer latch 53 with a stop 62 determines the operative position of the latch. The oscillation of the transerrer latch 53 swings the

upper end of the abutment 52 out of the path of movement of the end of the transferrer latch actuator 32, but the disengagement of the abutment 52 from the end of the actuator does not take place until after the bunter 61 has struck the rearward end of the transferrer latch 53. After the bunter 61 has contacted with the end of the latch 53, a shoulder 63 projecting rearwardly from 10 the latch 53 prevents the disengagement of the latch from the bunter.

It sometimes happens that the shuttle is not properly boxed in the shuttle box on the weft replenishing side of the loom, that 15 is to say, the shuttle does not come to rest in position to permit a bobbin with a fresh supply of filling to be inserted in the shuttle. If at such times the transferrer hammer is actuated to transfer a new bobbin 20 into the shuttle, a serious accident is likely to occur. To prevent such contingency, looms are commonly provided with a device known in the weaving art as a "revoker," which effectively prevents the operation of 25 the weft replenishing mechanism when the shuttle is improperly boxed. The filling engaging tip 26 of the present invention is so constructed that one part thereof, namely, the left-hand end 64 which projects 30 rearwardly toward the bobbin slightly farther than the right-hand end, performs the filling feeling function while the right-hand end 65 of the filling engaging tip is utilized as a revoker. The utilization of the right- 35 hand end of the filling engaging tip 26 as a revoker is effected by projecting the right-hand end of the filling engaging tip laterally a sufficient distance so that, when the shuttle is not properly boxed, the right- 40 hand end 65 of the filling engaging tip will come in contact with the front wall of the shuttle. The engagement of the part 65 of the filling engaging tip with the front wall of the shuttle prevents the shuttle engaging 45 tip 31 from contacting with the front wall of the shuttle when the filling has been exhausted to a predetermined extent; consequently, the feeler controller 30 is prevented from oscillating on its pivot, thereby 50 preventing the end of the transferrer latch actuator 32 from engaging with the abutment 52 of the transferrer latch. The failure of the transferrer latch actuator 32 to engage the abutment 52 results in the trans- 55 ferrer latch maintaining its inoperative position and the consequent non-operation of the filling replenishing mechanism. It is apparent, therefore, that the present construction of filling feeler eliminates the 60 necessity of providing the loom with a separate revoker.

So long as a substantial amount of filling remains on the bobbin in the active shuttle, the engagement of the filling engaging tip

by the filling prevents the engagement of 65 the shuttle engaging tip by the shuttle; but, when the filling has been exhausted to a predetermined extent, the shuttle engaging tip 31 is contacted by the front wall of the shuttle, as shown in Fig. 2, and the forward 70 end of the transferrer latch actuator is brought into engagement with the abutment 52. The continued forward movement of the lay pushes forward the actuator 32, thereby causing the transferrer latch 53 to 75 swing on its pivot 54 until the rearward end of the latch is positioned in the path of the advancing bunter 61. As the lay continues its forward movement, the pressure exerted upon the transferrer latch 53 oscillates 80 the transferrer hammer 56 on its pivot 57 until the bobbin engaging end of the transferrer hammer 56 strikes the bobbin in the compartment over the active shuttle, forcing 85 it into the shuttle; whereupon, the exhausted bobbin drops through the recess in the lay provided for that purpose. Immediately after the bunter 61 has engaged the rearward end of the latch 53 and before the filling replenishment takes place, the active 90 part 50 of the cam 36 strikes the roll 49 carried by the lever 38, so that the filling feeder 25 is retracted out of the shuttle in time for the filling replenishing operation.

Having thus illustrated and described a 95 specific embodiment of the invention, what is claimed is:—

1. A weft replenishing loom having, in combination, a lay, a bunter mounted on the lay, a shuttle, a weft replenishing mechanism including a transferrer latch, and a filling feeler mechanism mounted on the breast beam on the same side of the loom with the weft replenishing mechanism comprising, a filling feeler and a feeler controller having provision by virtue of which, when the filling in the shuttle is exhausted to a predetermined extent, the transferrer latch is positioned in the path of movement 100 of the bunter.

2. A weft replenishing loom having, in combination, a lay, a bunter on the lay, a shuttle, a weft replenishing mechanism having a transferrer latch, and a filling feeler mechanism mounted on the breast beam on the same side of the loom with the weft replenishing mechanism comprising, a filling feeler and a feeler controller including a transferrer latch actuator adapted, upon predetermined exhaustion of filling in the 115 shuttle, to actuate the transferrer latch so that it may be engaged by the bunter.

3. A weft replenishing loom having, in combination, a lay, a bunter, a shuttle, a weft replenishing mechanism, and a filling feeler mechanism located forward of the lay on the same side of the loom with the weft replenishing mechanism having provision 125

- by virtue of which, when the filling in the shuttle is exhausted to a predetermined extent, the weft replenishing mechanism is caused to effect filling replenishment, said 5 filling feeler mechanism comprising a filling feeler having a filling engaging tip constructed and arranged to prevent the operation of the weft replenishing mechanism when the shuttle is not properly boxed.
- 10 4. A weft replenishing loom having, in combination, a lay, a bunter mounted on the lay, a weft replenishing mechanism including a transerrer latch having an abutment, and a filling feeler mechanism comprising, 15 a filling feeler and a feeler controller having a transerrer latch actuator, said transerrer latch actuator being constructed and arranged to be out of engagement with the abutment when there is a substantial 20 amount of filling in the shuttle, and to contact with the abutment when the filling is exhausted to a predetermined extent to actuate the transerrer latch and bring it into the path of movement of the bunter.
- 25 5. A weft replenishing loom having, in combination, a lay, a bunter, a shuttle, a weft replenishing mechanism including a transerrer latch, and a filling feeler mechanism mounted on the breast beam on the 30 same side of the loom as the weft replenishing mechanism, said filling feeler mechanism comprising, a filling feeler, a controller, a cam, and connections between the filling feeler and the cam.
- 35 6. A weft replenishing loom having, in combination, a lay, a shuttle, a weft replenishing mechanism, and a filling feeler mechanism located forward of the lay having provision by virtue of which when filling in 40 the shuttle is exhausted to a predetermined extent, the weft replenishing mechanism is caused to effect filling replenishment, said filling feeler mechanism comprising a feeler controller adapted to be brought into engagement with a part of the weft replenishing mechanism on predetermined exhaustion of filling, and a filling feeler having a filling engaging tip constructed and arranged to prevent the operation of the 45 weft replenishing mechanism when the shuttle is not properly boxed on the weft replenishing side of the loom.
7. A weft replenishing loom having, in combination, a lay, a shuttle, a bunter 50 mounted on the lay, a weft replenishing mechanism including a transerrer latch and an abutment on the latch projecting upwardly therefrom, and a filling feeler mechanism mounted on the same side of the loom 55 with the weft replenishing mechanism comprising, a filling feeler and a feeler controller having a transerrer latch actuator being constructed and arranged to be out of engagement with the abutment when
- there is a substantial amount of filling in the shuttle, and to contact with the abutment when the filling is exhausted to a predetermined extent, to actuate the transerrer latch and bring it into the path of movement of the bunter.
8. A weft replenishing loom having, in combination, a lay, a bunter on the lay, a shuttle, a filling feeler mechanism comprising, a filling feeler, a feeler controller, and a transerrer latch actuator adapted to be in raised position when the shuttle does not contact with the controller, and to be depressed when the shuttle contacts with the controller on predetermined exhaustion of filling, and a transerrer mechanism including a latch, an abutment on the latch projecting upwardly into the path of movement of the transerrer latch actuator when the latter is depressed, and adapted to be engaged thereby to bring the latch into the path of movement of the bunter.
9. A weft replenishing loom having, in combination, a lay, a bunter on the lay, a shuttle, a filling feeler mechanism comprising, a filling feeler, a feeler controller, and a transerrer latch actuator adapted to be in raised position when the shuttle does not contact with the feeler controller, and to be depressed when the shuttle contacts with the controller, on predetermined exhaustion of filling, and a transerrer mechanism located on the same side of the loom with the filling feeler mechanism including a latch, an abutment on the latch projecting upwardly into the path of movement of the transerrer latch when the latter is depressed, and adapted to be engaged thereby to bring the latch into the path of movement of the bunter.
10. A weft replenishing loom having, in combination, a lay, a shuttle, a filling feeler mechanism comprising, a filling feeler movable toward and from the lay, a housing in which the filling feeler is received, a feeler controller mounted on the filling feeler having a transerrer latch actuator adapted to slide on the housing when the filling is exhausted to a predetermined extent, and a transerrer mechanism including a latch and an abutment on the latch, located adjacent the housing and projecting upwardly beyond the upper surface thereof and adapted to be engaged by the actuator when the latter slides on the housing.
11. A weft replenishing loom having, in combination, a lay, a bunter on the lay, a shuttle, a weft replenishing mechanism including a latch, filling feeler mechanism including a filling feeler, and a feeler controller having a latch actuator constructed and arranged to be brought into engagement with the latch to position it in the path of movement of the bunter on the beat.

up of the lay on which critical exhaustion of the filling in the shuttle is detected by the filling feeler mechanism.

12. A weft replenishing loom having, in combination, a lay, a bunter on the lay, a shuttle, weft replenishing mechanism having a latch, filling feeler mechanism including a filling feeler and a controller therefor

having a latch actuator constructed and arranged to be brought into engagement with the latch on the indication of critical exhaustion of filling in the shuttle by the filling feeler, to position it in the path of movement of the bunter.

WILLIAM H. RANKIN.
